UNITED STATES PATENT OFFICE.

FRED W. WOLF, OF CHICAGO, ILLINOIS.

COMPRESSOR.

1,295,947.

Specification of Letters Patent.

Patented Mar. 4, 1919.

Application filed December 4, 1916. Serial No. 134,792.

To all whom it may concern:

Be it known that I, FRED W. WOLF, a citizen of the United States, and a resident of Chicago, in the county of Cook and State 5 of Illinois, have invented certain new and useful Improvements in Compressors; and I do hereby declare that the following is a full, clear, and exact description thereof, reference being had to the accompanying 10 drawings, and to the letters of reference, marked thereon, which form a part of this specification.

This invention relates to improvements in compressors and consists of the matters 15 hereinafter described and more particularly pointed out in the appended claims.

One object of the invention is to provide a compressor which may be driven at a maximum of efficiency by means of a small 20 motor of low power, which is noiseless in operation and which is of cheap and economical construction.

Another object of the invention is to provide a compressor, suitable for use in connection with refrigerating apparatus and which has positive and mechanically operated 25 valves.

These and other advantages of the improved compressor will appear as I proceed with my specification.

In the drawings:

Figure 1 is a view representing a longitudinal, central section through the compressor.

Fig. 2 is a view showing a transverse section through the compressor in a plane indicated by the line 2-2 of Fig. 1.

Fig. 3 is a view illustrating a sectional end elevation of the compressor, the plane of the section being indicated by the line 3-3 of Fig. 1.

Fig. 4 is a perspective view of the movable member of the valve mechanism of the compressor.

Fig. 5 represents a transverse section through one of the valve chests and its associated cylinder.

Fig. 6 represents a transverse section through the Scotch yoke which forms part 50 of the crank mechanism of the compressor, the plane of the section being indicated by the line 6-6 of Fig. 1.

Fig. 7 is a view similar to Fig. 1, showing a modified form of the compressor.

Figs. 8 and 9 represent transverse sec-

tions through the valve chests and cylinders of the modified construction.

Fig. 10 is a perspective view of one of the movable members of the valve mechanism used in the modified construction.

Referring now to that embodiment of the invention illustrated in the accompanying drawings and particularly to that shown in Figs. 1 to 6 inclusive:

11 indicates as a whole the casing of the 65 compressor. Said casing consists generally of a cylindrical shell 12 and of two end members or heads 13, 13 which close the ends of said shell and which are provided with integral end-wise extending cylinders 70 14, 14. The cylinders have their central axes in the same line which is coincident with the central axis of the cylindrical shell 12. The heads 13 are in the form of circular plates 13^a made integral with the cylinders and having radial ribs 13^b which brace and support the cylinders 14 beyond said plates. The plates 13^a are secured to the ends of the cylindrical shell 12 by screws or in any other convenient manner. 80

15 indicates the driving shaft of the compressor. Said shaft is mounted in the shell 12 intermediate the ends of the shell (as shown half way between said ends) and is located in a horizontal plane with its longitudinal central axis intersecting the line of the axes of the cylinders 14, 14. Said shaft has bearing in plates 16, 17 fixed to the sides of the shell 12 at suitable alined bearing openings formed in said shell. 90

The plate 16 has a bearing sleeve 16^a made integral with it and braced by means of connecting radial ribs 16^b. Said sleeve provides bearing for one end of the shaft 15, but is spaced somewhat from the plate 16 to allow room for an end thrust disk 15^a fixed to the end of the shaft and acting to distribute the thrust of the shaft over a large surface of the plate 16. The plate 17 has a journal box 18 made integral with it 100 and projecting from its outer face. An annular flange 19 on its inner face provides a stuffing box which is closed by a gland 20 mounted on the shaft 15. Contractile, coiled springs 21 connecting a radial flange 105 22 of the said gland with fixed parts on the bearing plate 17, yieldingly hold the packing within the stuffing box and pins or studs 23 extending inwardly from said plate and engaged in suitable apertures in the said 110

flange 22 hold the gland against rotation. A driving pulley 24 is fixed to the driving shaft adjacent the journal box 18.

- 25 indicates what is familiarly known as a Scotch yoke, mounted in a vertical plane within the shell 12 and adapted for longitudinal reciprocable bearing engagement therein, in the line of the cylinders 14, 14. Said yoke carries oppositely disposed pistons 26 at its ends, each piston being capable of reciprocation in an associated cylinder 14. Within the yoke is mounted a vertically reciprocating block 27 in which an eccentric disk 28, fixed to the shaft 15, has bearing.
- 10 Thus the rotation of the shaft 15 produces a reciprocatory movement of the yoke and in consequence the required reciprocation of the pistons 26 in their respective cylinders.

The yoke 25 is preferably made of two U-shaped plates or bars each consisting of an upright member 29 with the associated piston 26 extending from one side of it and of two horizontal members 30, 30 which form the legs of the U. The horizontal legs 30 of the opposing U-plates forming the yoke are provided with end tongues or extensions 31 and intervening notches which dove-tail together as shown in Fig. 6. The U-plates or bars are held together and braced by means 30 of tie rods and spacing sleeves 32 located at the sides near the top and bottom of the yoke. The block 27 is provided at its ends with vertical ribs which have guiding engagement in suitable grooves or ways formed 35 on the inner faces of the vertical members 29 of the U-plates of the yoke.

At one side of each cylinder 14 is formed a tubular valve chest 33, with its longitudinal central axis parallel to that of the cylinder. 40 As illustrated herein, the tubular valve chests of the two cylinders have their longitudinal central axes in the same line as in the case of the cylinders and the movable member of the valve is in each case a rotary member which is made integral with a shaft common to both. 34, 34 indicate the rotary valve members and 35, the common shaft connecting the two.

In the preferred construction, the shaft 35 50 and the two valve members 34 are turned from a single rod or bar which is bored longitudinally to provide a passage-way 36. (See Fig. 4.) Each valve part 34 is of the diameter of the bore of its valve chest in 55 which it rotates. It is provided on one side with an inlet port 37 which is adapted at one point of its rotation to come to register with a port 38 at the end of its associated cylinder 14. On its opposite side and diametrically opposed to the port 37, the valve member 34 is provided with a longitudinal groove 39, one part of which is adapted to be brought to register with the port 38 in the associated cylinder. Said groove, at the end 60 toward the cylinder head is closed. Its other

end is open and connects with the interior of the shell 12, so that said groove acts as a discharge port and passage for the delivery of the compressed fluid to said shell.

In turning the rod or bar to form the two rotary valve members and their common shafts, the shaft 35 intermediate the two valve members, and the ends 35^b beyond said valve members are made of reduced diameter and the latter have suitable bearing in the outer ends of their respective valve chests. One valve chest is closed at its outer end. (See Fig. 1.) The other is provided with a threaded aperture in line with the bore of the valve members 34 and of their common shaft, and a nipple 40 engaged in said aperture, provides for the attachment of a conduit pipe (not shown) leading from the source of the supply of low pressure fluid that is to be compressed:—as for example, 85 in the case of the use of the compressor in connection with a refrigerating apparatus, when said conduit would connect the compressor with the expansion coil of the apparatus.

90 The compressed fluid discharged into the shell 12, which incloses what may be called the crank case of the compressor, is led therefrom through an outlet nipple 41 which may be connected to any suitable receiver (not shown), as for example, the condenser of a refrigerating apparatus. Said outlet nipple as illustrated, is located in the bottom of the crank case, where it may be placed with propriety, when the oil used for lubrication will 95 have no deleterious effect upon the fluid that is to be compressed, as when the oil is circulated through the system. When it is required to retain the oil in the crank case, said outlet would be placed at the top of the 100 crank case.

105 The shaft of the rotary valve member is driven by suitable connections to the drive shaft 15. A worm gear 35^b on the valve shaft 35 is engaged by a worm 15^x on the 11 shaft 15. Said gear and worm are designed to produce the rotary movement of the valves 34 in the proper timed relation to the reciprocatory movement of the pistons. It will of course be understood that the discharge port and passage 39 of one valve member 34 is in line with the inlet port 37 of the other valve member (as clearly shown in Fig. 4) so that one cylinder is discharging when the other cylinder is drawing in 11

12 The operation of the compressor is apparent from the foregoing description. The rotation of the shaft 15 produces a reciprocatory movement of the yoke 30 in the crank case and similar movement of the pistons 26 in their respective cylinders. As the discharge and inlet ports are separated by an angle of 180°, it is apparent that after the fluid has been discharged from a cylinder

at the end of the stroke of its piston, a considerable part of the return stroke will have been accomplished, before the associated inlet port is brought to a position to admit fluid to the cylinder. Thus a vacuous condition is produced, with the result that there is a rapid flow of fluid into the cylinder when the inlet port is opened and the cylinder is completely filled with the fluid to be compressed. In like manner, on the discharge stroke of the piston, the discharge port is not opened until the piston has approached the end of its discharge stroke, so that the fluid is compressed above the pressure in the crank casing before being delivered to said casing, with the result that the cylinder is completely emptied.

The action of the valves is definite and positive and exactly predetermined, and apparently they will operate without noise. The pressure upon the ends of the yoke will be balanced at all times and therefore the high pressure in the crank case will have no effect to increase the power required to operate the pistons. Side thrust on the pistons is entirely eliminated, since bearing support for the pistons is provided by the yoke, which as has been pointed out, has reciprocable bearing in the shell, and the pistons themselves may be aptly called "floating pistons."

The stuffing box inclosed by the flange 19, being on the inside of the crank case, is what may be termed an oil-wet and an oil-cooled stuffing box. The oil is continuously renewed from the crank case and is supplied to the stuffing box under the high pressure that exists in the crank case. This increases the efficiency of the seal provided by the stuffing box and prolongs the life of the packing.

In the modification shown in Figs. 7 and 10, the construction of the compressor is in every way similar to that above described, excepting in the matter of the valves. In this case, there are provided separate inlet and outlet rotary valve members for each cylinder and separate valve chests for the same. The parts that are unchanged are indicated by the same reference numerals.

42, 43 indicate the valve chests of the cylinders 14^x, 14^x of the modified construction of the compressor. The valve chests 42 contain the inlet valves and the valve chests 43 contain the outlet or discharge valves.

The discharge valve is illustrated in Fig. 10. It includes the rotary valve members 34^x, 34^x and the intermediate common shaft 34^y as before. The valve members and the connecting valve shaft are hollow and the valve members are provided near their ends with discharge ports 39^x, 39^x. The said discharge ports, instead of discharging alongside the common shaft as in the other case, in the modification, discharge into the in-

terior of the bore of the shaft which is provided intermediate the valve parts with a plurality of ports 39^y for the direct discharge into the crank casing.

The inlet valve is identical with the discharge valve except that its connecting shaft contains no openings connected with the crank case. Instead, one open end connects with the inlet nipple as heretofore described. The ports 37^x of each valve part are in this case inlet ports. It will be understood, of course, that in the modification, the inlet ports 37^x of the one valve and the discharge ports 39^x of the other valve are spaced apart an angular distance of 180 degrees.

Each valve chest 42, 43 is connected with its associated cylinder by means of ports 42^a, 43^a, one of which, 42^a, is always an inlet port and the other of which is always an outlet or discharge port. Each valve member is provided with a worm gear 35^x which is engaged by the common worm 35^y on the drive shaft.

The operation of the modified compressor needs no particular description. The only difference between the two is that the inlet of the fluid to be compressed to each cylinder is controlled by one member while the discharge from said cylinder is controlled by another member. Both members, however, are driven from the same common driving shaft. The final result is just the same.

While in describing my invention I have referred to certain details of construction and of mechanical arrangement, it is to be understood that the invention is to be in no way limited thereby, except as pointed out in the appended claims.

I claim as my invention:

1. A compressor, comprising a casing consisting of a shell and of heads provided with oppositely disposed cylinders, pistons reciprocable in said cylinders, a drive shaft mounted in said shell, means intermediate said drive shaft and said pistons for reciprocating them in unison, valve mechanism associated with each cylinder adapted to discharge into the said shell, and means intermediate said shaft and said valve mechanism for operating said valve mechanism.

2. A compressor, comprising a casing consisting of a shell and of heads provided with oppositely disposed cylinders, "floating" pistons reciprocable in said cylinders, a drive shaft mounted in said shell, means intermediate said drive shaft and said pistons for providing bearing reciprocable support for them and for reciprocating them in unison, valve mechanism associated with each cylinder adapted to discharge into the said shell, and means intermediate said shaft and said valve mechanism for operating said valve mechanism.

3. A compressor, comprising a casing con-

sisting of a shell and of heads provided with oppositely disposed cylinders, pistons reciprocable in said cylinders, a drive shaft mounted in said shell, means intermediate 5 said drive shaft and said pistons for reciprocating them in unison, valve mechanism associated with each cylinder adapted to discharge into said shell and comprising a tubular valve casing and a cylindrical valve member movable therein, and means intermediate said shaft and said valve mechanism for operating said valve mechanism.

4. A compressor, comprising a casing consisting of a shell and of heads provided with 15 oppositely disposed cylinders, "floating" pistons reciprocable in said cylinders, a drive shaft mounted in said shell, means intermediate said drive shaft and said pistons for providing bearing reciprocable support 20 for them and for reciprocating them in unison, valve mechanism associated with each cylinder adapted to discharge into said shell and comprising a tubular valve casing and a cylindrical valve member movable therein, and means intermediate said shaft and 25 said valve mechanism for operating said valve mechanism.

5. A compressor, comprising a casing consisting of a shell and of heads provided with 30 aligned, oppositely disposed cylinders, a drive shaft mounted in said shell with its axis at right angles to the axis of said cylinders, a yoke adapted to be reciprocated in said shell by said drive shaft, pistons connected to 35 said yoke, valve mechanism associated with each cylinder adapted to discharge into said shell, and means intermediate said shaft and said valve mechanism for operating said valve mechanism.

40 6. A compressor, comprising a casing consisting of a shell and of heads provided with opposite disposed cylinders, pistons reciprocable in said cylinders, a drive shaft mounted in said shell, means intermediate said drive shaft and said pistons for reciprocating them in unison, valve mechanism associated with each cylinder adapted to discharge into said shell, said valve mechanism comprising a valve casing and a valve member rotative therein, and means intermediate said shaft and said valve mechanism for operating said valve mechanism.

7. A compressor, comprising a casing consisting of a shell and of heads provided with 55 oppositely disposed cylinders, "floating" pistons reciprocable in said cylinders, a drive shaft mounted in said shell, means intermediate said drive shaft and said pistons for providing bearing reciprocable support for them and for reciprocating them in unison, valve mechanism associated with each cylinder adapted to discharge into said shell, said valve mechanism comprising a valve casing and a valve member rotative therein, 60 and means intermediate said shaft and said

valve mechanism for operating said valve mechanism.

8. A compressor, comprising a casing consisting of a shell and of heads provided with oppositely disposed cylinders, pistons reciprocable in said cylinders, a drive shaft mounted in said shell, means intermediate said drive shaft and said pistons for reciprocating them in unison, valve mechanism associated with each cylinder adapted to discharge into the said shell consisting of a valve casing and of a valve plug rotative in said casing, a common shaft connecting the rotative valve members associated with the two cylinders, and gearing intermediate 75 said valve shaft and said drive shaft.

9. A compressor, comprising a casing consisting of a shell and of heads provided with oppositely disposed cylinders, a drive shaft mounted in said shell, a yoke reciprocable in said shell, said yoke consisting of two U-shaped bars each of which has a piston reciprocable in said cylinders, means connecting the said U-shaped bars together, a block reciprocable in said yoke, an eccentric fixed to said shaft in the plane of said yoke and operatively engaged in said block, a gear on said drive shaft, a rotative tubular valve member associated with each cylinder and adapted to discharge into said shell, said valve members having a common connecting shaft, and a gear on said common connecting shaft meshing with the gear on said drive shaft.

10. A compressor, comprising a casing consisting of a shell and of heads fixed to the ends of said shell, said heads having oppositely disposed cylinders and oppositely disposed valve chests, the associated cylinder and valve chest of each head having a communicating passageway, pistons reciprocable in said cylinders, a yoke operatively connecting said pistons so that they reciprocate in unison, a drive shaft mounted in said shell, means intermediate said yoke and shaft for reciprocating said yoke, a tubular rotative valve member mounted in said valve chests, said valve member having ports and grooves adapted to register with the communicating passageways between said cylinders and said valve chests, the ports in said valve member operatively connecting said cylinders with the interior of said tubular valve member and said grooves operatively connecting said cylinders with the interior of said shell, and gearing between said valve member and shaft for rotating said valve member.

11. A compressor, comprising a casing consisting of a shell and of heads fixed to the ends of said shell, said heads having cylinders arranged in line, a transverse shaft journaled in said shell, a yoke reciprocated in said shell, and operatively driven from said drive shaft, said yoke consisting of two

U-shaped bars each of which has an integral piston head reciprocable in an associated cylinder, each of said U-shaped bars comprising upright members and horizontal members, said horizontal members having inter-engaging tongue and groove connections, said horizontal members being adapted for sliding bearing upon the inner surface of said shell, and spacing means connecting the upright members of said U-shaped bars together.

12. A compressor, comprising a casing consisting of a shell and of heads provided with oppositely disposed cylinders, a transverse drive shaft journaled in said shell, a reciprocating yoke in said shell, said yoke consisting of two U-shaped bars each of which has an integral piston head recipro-

cable in an associated cylinder, each of said bars comprising an upright member having a vertical groove in its inner face and of horizontal members engaging each other at their ends, a vertically reciprocating block having ribs engaged in the grooves of said upright members, an eccentric disk fixed to said shaft and rotatable in said block and spacing means connecting the upright members of said U-shaped bars together.

In testimony that I claim the foregoing as my invention I affix my signature in the presence of two witnesses, this 22nd day of November A. D. 1916.

FRED W. WOLF.
